(57) **CLAIM**

The ornamental design for a plunger rod for a medical syringe, as shown and described.

DESCRIPTION

FIG. 1 is front elevation view of a plunger rod for a medical syringe in accordance with the embodiment of the ornamental design;

FIG. 2 is back elevation view of the plunger rod for a medical syringe of FIG. 1;

FIG. 3 is top plan view of the plunger rod for a medical syringe of FIG. 1;

FIG. 4 is a bottom plan view of the plunger rod for a medical syringe of FIG. 1;

FIG. 5 is a right side elevation view of the plunger rod for a medical syringe of FIG. 1;

FIG. 6 is a left side elevation view of the plunger rod for a medical syringe of FIG. 1;

FIG. 7 is a perspective view of the plunger rod for a medical syringe of FIG. 1;

FIG. 8 is an enlarged view of a portion of the plunger rod for a medical syringe of FIG. 1;

FIG. 9 is a sectional view along line 9-9 (FIG. 1) of the plunger rod for a medical syringe of FIG. 1; and,

FIG. 10 is a sectional view along line 10-10 (FIG. 1) of the plunger rod for a medical syringe of FIG. 1.

The appearance of elements presented in broken line format, including the shaft and distal end of the plunger rod for a medical syringe, form no part of the claimed invention.
